CLAIM

The ornamental design for an aroma nebulizing diffuser, as shown and described.

DESCRIPTION

FIG. 1 is a perspective view of an aroma nebulizing diffuser showing my new design;
FIG. 2 is the other perspective view thereof;
FIG. 3 is a front elevation view of FIG. 1;
FIG. 4 is a rear elevation view of FIG. 1;
FIG. 5 is a left side elevation view of FIG. 1;
FIG. 6 is a right side elevation view of FIG. 1;
FIG. 7 is a top plan view of FIG. 1; and,
FIG. 8 is a bottom plan view of FIG. 1.

1 Claim, 7 Drawing Sheets
